UNITED STATES PATENT OFFICE.

FREDERICK B. TOWNSEND, OF CHICAGO, ILLINOIS, ASSIGNOR, BY MESNE ASSIGNMENTS, TO W. H. MINER COMPANY, OF CHICAGO, ILLINOIS, A CORPORATION OF ILLINOIS.

ROCKER SIDE BEARING FOR RAILWAY-CARS.

SPECIFICATION forming part of Letters Patent No. 725,380, dated April 14, 1903.

Application filed December 31, 1902. Serial No. 137,264. (No model.)

To all whom it may concern:

Be it known that I, FREDERICK B. TOWNSEND, a citizen of the United States, residing in Chicago, in the county of Cook and State 5 of Illinois, have invented a new and useful Improvement in Rocker Side Bearings for Railway-Cars, of which the following is a specification.

My invention relates to improvements in 10 rocker side bearings for railway-cars, and more particularly to improvements upon the gravity-rocker side bearing forming the subject of United States Patents No. 646,986, of April 10, 1900, No. 668,642, of February 26, 15 1901, and No. 715,577, of December 9, 1902.

The object of my invention is to provide a rocker side bearing in which the base or bottom plate and reciprocating top plate are secured together by interfitting guides or flanges 20 and which will at the same time admit of the rockers being inserted in position between the top and bottom plates after the top and bottom plates are assembled and locked together by their interfitting guides or flanges.

25 My invention consists in the means I employ to practically accomplish this object or result—that is to say, it consists, in connection with the base or bottom plate, reciprocating top plate, and a pair of gravity-returning rockers, in providing the bottom plate with openings therein through which the rockers may be inserted in position between the top and bottom plates, said openings in the bottom plate being closed by separate sections 30 which are adapted to be fixed in place after the rockers are in position.

35 My invention further consists in the novel construction of parts and devices and in the novel combination of parts and devices herein 40 shown or described.

In the accompanying drawings, forming a part of this specification, Figure 1 is a perspective view of a rocker side bearing embodying my invention. Fig. 2 is a vertical 45 section on line 2 2 of Fig. 3. Fig. 3 is a vertical section on line 3 3 of Fig. 1. Fig. 4 is a detail plan of the base or bottom plate.

In the drawings, A represents the body-bolster, and A' the truck-bolster, of a railway- 50 car.

B is the bottom or base plate of the side bearing, the same or its tread B' being curved on the arc of a circle whose center is the king-bolt on which the bolster turns. The bottom plate B is provided with upright side 55 guides b, having projecting flanges b'.

D is the reciprocating top plate of the side bearing, the same having downwardly-projecting side guides d and flanges d', the guides and flanges d d' interfitting and engaging with 60 the guides and flanges b b' to hold the top and bottom plates together, while permitting the top plate to reciprocate in respect to the bottom plate.

To adapt the rockers F F to be inserted upwardly through the bottom plate into position between the top and bottom plates, the bottom plate is provided with openings b² large enough to admit the rockers through the same. These openings b², one for each rocker, are 70 closed by removable sections B², having flanges b³ with rounded corners b⁴, so that after the rockers are inserted and the sections B² in place they may be secured in position by upsetting the marginal edges b⁵ of the 75 openings b². The gravity returning rockers F F have each a large curved lower bearing-face f and a small curved upper bearing-face f', the bearing-faces being concentric with each other. The rocker-tread B' of the bottom plate is formed on the removable sections B² B² and is convex or double inclined, as illustrated in the drawings, to prevent lodgment of dirt or cinders thereon. The outer end f² of each rocker is larger than its 80 inner end f³, thus giving the rocker a somewhat tapering or conical shape, as indicated by the broken lines X X in Fig. 2, to compensate for the curvature of the tread B' about the king-bolt as a center. The top plate D is 85 provided with curved segmental sockets or bearings d³ to receive the upper small bearing-faces f' of the rocker. The side guides d of the top plate D are provided with recesses d⁴ to receive the projecting ends or studs f⁵ of 90 the rockers and by which in connection with the curved sockets or bearings d³ the reciprocating top plate is connected to the gravity-rockers and caused to return to position when the rockers return to their normal or 95 100

central position by the gravity action of their large lower bearing-faces. The rockers F F are each provided on its lower bearing-face f^5 with a central row of teeth f^6 , which mesh 5 with corresponding teeth b^5 on the separate section B^2 of the base or bottom plate. The top plate D is provided with a central transverse web d^6 and the bottom plate with a central transverse web b^6 .

- 10 To assemble my rocker side bearing, the top plate is first slid or telescoped onto or over the bottom plate. The rockers F F are next inserted upwardly through the openings b^2 in the bottom plate and the separate 15 or removable sections B^2 B^2 put in position and then secured in place by any suitable means—such, for example, as upsetting the marginal edges b^5 of the opening b^2 . After the movable sections B^2 are thus fixed in position all the parts of the rocker side bearing 20 are securely united together, so that they cannot become separated in use or lost.

I claim—

1. In a rocker side bearing, the combination 25 with a bottom plate of a reciprocating top plate, said plates being provided with interfitting guides and flanges, rockers interposed between the top and bottom plates, said bottom plate being provided with openings through the same through which the 30 rockers may be inserted in position, substantially as specified.

2. In a rocker side bearing, the combination 35 with a bottom plate of a reciprocating top plate, said plates being provided with interfitting guides and flanges, rockers interposed between the top and bottom plates, said bottom plate being provided with openings through the same through which the 40 rockers may be inserted, and separate sections closing the openings in the bottom plate, substantially as specified.

3. In a rocker side bearing, the combination 45 with a base or bottom plate having openings through the same for the insertion of rockers and provided with separate sections for closing said openings, of a reciprocating top plate and interposed rockers, substantially as specified.

4. In a rocker side bearing, the combination 50 with a bottom plate having openings through the same for the insertion of rockers, of separate sections closing said openings, rockers, and a reciprocating top plate, said top and bottom plates having interfitting 55 guides and flanges to hold the plates together while permitting the top plate to reciprocate, substantially as specified.

5. In a rocker side bearing, the combination 60 with a bottom plate having openings through the same for the insertion of the rockers, separate tread bearing-sections closing said openings, rockers, and a reciprocating top plate, substantially as specified.

6. In a rocker side bearing, the combination 65 with a bottom plate having openings through the same for the insertion of the rockers, separate tread bearing-sections closing said openings, rockers and a reciprocating top plate, said top and bottom plates having 70 interfitting side guides and flanges, substantially as specified.

7. In a rocker side bearing, the combination 75 with a bottom plate having openings through the same for the insertion of the rockers, separate tread bearing-sections closing said openings, rockers and a reciprocating top plate, said top and bottom plates having interfitting guides and flanges, and said 80 rockers and said separate tread-sections of the bottom plate being provided with intermeshing teeth, substantially as specified.

8. In a rocker side bearing, the combination 85 with a bottom plate having openings through the same for the insertion of the rockers, separate tread bearing-sections closing said openings, rockers and a reciprocating top plate, said top and bottom plates having interfitting side guides and flanges, and said 90 separate tread bearing-sections of the bottom plate having rounded marginal edges and being secured in the bottom plate by upsetting the marginal edges of the openings therein, substantially as specified.

FREDERICK B. TOWNSEND.
